FIG. 1

FIG. 2

Ivan Ročić
INVENTOR.

UNITED STATES PATENT OFFICE

92,978

DESIGN FOR A COMBINATION GRIDDLE PLATE, BROILER, AND TOASTER

Ivan Ročić, New York, N. Y.

Application June 4, 1932, Serial No. 43,982

Term of patent 14 years

To all whom it may concern:

Be it known, that I, IVAN Ročić, a citizen of the Kingdom of Croatia, Jugoslavia, and a resident of the city of New York, county of New York, and State of New York, have invented a new, original, and ornamental Design for a Combination Griddle Plate, Broiler and Toaster, of which the following is a specification, reference being had to the accompanying drawing forming part thereof,

Figure 1 is a perspective view looking down from the top, of a combination griddle plate, broiler and toaster, showing my new design.

Figure 2 is a side elevational view thereof.

I claim:—

The ornamental design for a combination griddle plate, broiler and toaster as shown.

IVAN ROČIĆ,
